VERTICALLY ARRANGED HAMMER MILL

Filed June 17, 1950

FIG. 2

FIG. 1

INVENTOR.
JAMES BROUH
BY A.S. Knob
ATTORNEY

trically mounted on the upper side of said frame plate, fan blades mounted on the upper end of the shaft of said motor and adapted to move air downwardly, the lower end of the shaft of said motor protruding for a distance through said frame plate, a generally circular in cross section housing for said motor and concentric therewith and mounted on the top of said frame plate and forming an air passageway around the motor, a number of ports in said frame plate and circumferentially spaced between the mounting of said motor and housing, one of said ports adapted to act as a feed passageway port and the others being adapted to act as air outlets from said housing, said housing being extended inwardly to partially surround said feed passageway port, a feed inlet member adapted to cooperate with said housing inwardly extending portion to form a feed hopper, a circular plate having a diameter substantially equal the diameter of said housing and being secured a distance below said frame plate by means of a number of spaced bolts, a circular screen detachably mounted between said frame plate and circular plate having a diameter substantially the general diameter of said housing cooperating with said frame and circular plate to form a hammer chamber, a number of vertically spaced hammer arms mounted on said protruding end of the motor shaft, a circular outlet duct having a diameter somewhat larger than

said circular plate and extending downwardly from the frame plate past the circular plate forming an outlet for the ground feed.
